(57) **CLAIM**

The ornamental design for a tube depth marking tool, as shown.

DESCRIPTION

FIG. 1 is a front elevational view of a tube depth marking tool in accordance with the present design;

FIG. 2 is a back elevational view thereof;

FIG. 3 is a top plan view thereof;

FIG. 4 is a bottom plan view thereof;

FIG. 5 is a side elevational view thereof;

FIG. 6 is an opposite side elevational view thereof; and,

FIG. 7 is an isometric view thereof.

The broken lines depict portions of the tube depth marking tool in which the design is embodied that are not considered part of the claimed design.
